UNITED STATES PATENT OFFICE.

JOHN P. THOMPSON, OF FALL RIVER, ASSIGNOR OF ONE-HALF TO THE WHITIN MACHINE WORKS, OF WHITINSVILLE, MASSACHUSETTS.

CARDING-MACHINE.

SPECIFICATION forming part of Letters Patent No. 443,415, dated December 23, 1890.

Application filed November 8, 1887. Serial No. 254,619. (No model.)

To all whom it may concern:

Be it known that I, JOHN P. THOMPSON, of Fall River, in the county of Bristol and State of Massachusetts, have invented certain new and useful Improvements in Carding-Machines, of which the following is a full, clear, and exact description, reference being had to the accompanying drawings, forming part of this specification.

10 This invention relates to a carding machine or engine for opening and straightening out cotton, wool, or other fiber.

The object of my invention is to provide what may be termed a "double card," which 15 will prove an efficient and economical machine.

To the aforesaid purposes my invention, briefly stated, consists, essentially, in having the licker-in, the carrier-cylinder, and doffer-roll arranged in the stated order intermediate the lap-roll and the main cylinder, in having a set of feed-rolls posterior to the lap-supply roll and a set of feed-rolls anterior to the main cylinder, in having the vibrating 25 packer co-operating with the doffer-roll and the doffer and the feed-rolls posterior thereto, in having the traveling conveying-apron for conveying the lap partly through the machine, and in the construction of the vibrating 30 packer and the vibrating doffer.

In order that my invention may be fully understood, I have illustrated in the accompanying drawings and will proceed to describe the best forms thereof so far devised 35 by me, with the knowledge, however, that such forms admit of modifications.

In the accompanying drawings, Figure 1 is a side view of my improved carding-machine, shown with part of the main cylinder and 40 framing omitted. Fig. 2 is an enlarged side view of a portion of the machine shown in Fig. 1, and shows the drive-shaft and the rock-shaft with the doffer and the packer and the intermediate connections. Fig. 3 is a front 45 view of the part shown in Fig. 2. Fig. 4 is a horizontal sectional view of the parts shown in Fig. 2, the section being taken on line 44 of Fig. 2. Fig. 5 is an enlarged side view of a part of the machine shown in Fig. 1, with 50 some of the side framing removed and showing more clearly the endless conveying-apron

under the packer. Fig. 6 is an enlarged detached view of the packer, with the rock-shaft and the loose sleeve of the packer shown in cross-section. Fig. 7 is a sectional view of the 55 packer, taken on line 77 in Fig. 6, viewed in the direction of the arrow therein shown, and shows the toothed packer-blades in advance of the toothless blade. The blades in this view have central sections shown as broken 60 away. Fig. 8 is a sectional view of the packer, taken on line 88 in Fig. 6, and shows the toothless packer-blade broken away at the center. Fig. 9 is a view of another form of packer, the view being similar to that 65 shown in Fig. 6. Fig. 10 is a sectional view of the packer, taken on line 1010 in Fig. 9. Fig. 11 is a side view of still another form of packer. Fig. 12 is an enlarged view in detail of a portion of the packer plate or blade 70 shown in Figs. 9 and 10, with a packer finger or tooth mounted therein.

In the said drawings like numbers of reference designate corresponding parts throughout.

75 Referring to the drawings, the number 3 designates the ordinary machine-framing, at the right-hand end of which is mounted the lap-supply roll 30, which supplies the fiber to the feed-rolls 31, and 32 is the licker-in, 4 the carrier-cylinder, and 5 is the doffer-roll, from whence the lap passes through the feed-rolls 16 to the main cylinder 33. The aforesaid card-cylinders are provided with the usual card-clothing and are mounted to turn in 80 their bearings in a manner well known. Likewise the feed-rolls 31 and 16 are rotary rolls of the ordinary construction, which may have one of each set given a positive motion in the usual manner.

90 My invention consists in part in the disposition or relative arrangement of these several old devices, together with the novel features, which I will now proceed to describe.

Near the doffer-roll 5, to the left thereof in 95 the view shown in Fig. 1, the drive-shaft 11 is mounted in the bracket 35, formed with the recess 37, and the shaft is provided with the pulley 12, which is rotated by the belt 13, receiving its motion from the band-pulley 14, 100 driven by the counter-shaft 15. In the bracket 35 is also mounted the rock-shaft 7, the other

end of which has a bearing (not shown) on the other side of the machine, and this shaft is provided with the fixed rocker-arm 9, by means of which the shaft may be rocked in 5 its bearings indirectly by the drive-shaft 11 through means of the eccentric 36, formed on the drive-shaft and the eccentric-rod 10, connecting the eccentric with the rocker-arm 9 by the pivot 38. Upon the rock-shaft 7 is 10 rigidly secured a pair of arms 39, only one of which is shown, the omitted one being located upon the opposite side of the machine from the one shown, and these arms carry the ordinary doffer-comb 6, which is given a 15 vibratory motion by means of the rock-shaft and acts to strip the fleece from the doffer-roll 5 in the ordinary manner.

My novel packer 17 strikes upon and packs and presses the fleece into a sheet after the 20 same is stripped from the doffer-roll by the doffer-comb, and is given a vibratory motion by the shaft 11 similar to the motion which is given to the doffer-comb by means of the rock-shaft 7. The packer consists in a sleeve 25 18, mounted loosely on the rock-shaft 7 and provided with the internal bearing-ridges 19, and having the packer-arms 20 cast thereon and each formed at the end with the eye 40 to receive the bolt 41 for attaching to the arms 30 the packer blades or plates 21, which are provided with the packer teeth or fingers 22. The sleeve 18 has a rocking motion imparted to it by the drive-shaft 11, so as to vibrate the packer through the following means: To 35 the sleeve is rigidly secured by the screw 43 the bent rock-arm 42, which projects over into the recess 37 of bracket 35, and to the end of which is pivoted by means of the pin 44 the eccentric-bar 45, which is connected by 40 its other end to the eccentric 36.

The packer teeth or fingers 22 may be formed integral with the blades, or they may be separate pieces inserted in the blades, as shown in Figs. 9, 10, and 12, wherein the tooth 22 is a 45 cylindrical plug having a forked or notched lower end 46.

In the construction of the packer shown in Figs. 6, 7, and 8 and the preceding figures there are used a set of toothed blades, together with one toothless blade, and these 50 blades are formed with perforations to receive the bolts and are arranged apart and parallel with the spacing-pieces 47 therebetween. In the forms shown in Figs. 9 and 11 there is 55 only one blade 21 used, which in the former instance is provided with teeth 22, and in the latter construction is a toothless flat blade L-shaped in transverse section.

Beneath the packer and doffer is disposed 60 my improved conveying-apron 48, disposed between the doffer-roll 5 and the feed-rolls 16. This apron is endless and is mounted on the rolls 49, any one of which may be given a positive rotary motion in a suitable way, so 65 as to keep the apron in constant motion in the direction from the doffer-roll toward the feed-rolls 16.

In Fig. 5 a band-pulley is shown in broken lines secured to one end of the lower feed-roll 16, and a similar band-pulley is shown secured to the end of the shaft of the roll 49 immediately under the packer. These two band-pulleys are shown connected with a driving-band, thus imparting motion to the belt 48, delivering the packed fiber to the 75 feed-rolls 16 at the same speed at which the feed-rolls deliver the fiber to the carding-cylinder.

In the operation of the card the cotton-bat passes from the lap-roll 30 through the feed-rolls 31, whence it is taken by the licker-in 32 and the carrier-cylinder 4 to the doffer-roll 5 to open the lap and partially clean and straighten the fiber, which is stripped from roll 5 by the doffer-comb 6, and, coming under the blows of the packer 17, is packed and thence carried by the apron 48 to the feed-rolls 16, whence it passes to the main cylinder 33.

Having thus described my invention, I 90 claim as new and desire to secure by Letters Patent—

1. In a carding-engine, the combination, with the main carding-cylinder, of the following successively-operating instrumentalities: 95 a lap-supporting roll, a pair of feed-rolls, a licker-in, a carrying-cylinder, a doffer-roll and doffer-comb, a carrying-apron, a fiber-packing device, and a pair of feed-rolls, all constructed to feed the lap to the licker-in, carry the fiber 100 from the licker-in to the doffer-roll, doff the fiber, pack the doffed fiber, and feed the packed fiber to the main carding-cylinder, as described.

2. The combination, in a carding-engine, 105 with the feed-rolls and the licker-in, of a carrying-cylinder, a doffing-cylinder and doffing-comb, a packing mechanism, an endless apron for conveying the packed fiber, and a pair of feed-rolls constructed to feed the 110 opened, doffed, and packed fiber to the main carding-cylinder, as described.

3. The combination, in a carding-engine with the main cylinder and a pair of feed-rolls adapted to feed the fiber directly to the 115 main cylinder, of mechanism for preparing the fiber, consisting of a pair of feed-rolls for feeding the lap to the licker-in, a licker-in for opening the lap, a carrying-cylinder, and a doffer-roll for carrying and condensing the 120 fiber, provided with a doffer-comb, a reciprocating packer mechanism, and a carrying-apron, all constructed to open the lap, partially straighten and clean the fiber, collect, condense, and pack the fiber, and deliver the 125 packed fiber to the feed-rolls adjacent the main cylinder, as described.

4. The combination, as hereinbefore set forth, with a shaft and a loose sleeve mounted thereon and provided with the packer and having a rigid arm secured thereto, of a drive-shaft having an eccentric and an eccentric-rod intermediate the said eccentric and the arm on the sleeve, whereby the sleeve may be

rocked on its shaft, substantially as and for the purpose herein described.

5. The combination, as hereinbefore set forth, with the rock-shaft having the rock-arm secured thereto and provided with the doffer and the loose sleeve mounted on the rock-shaft and provided with the packer and having a rigid arm thereon, of a drive-shaft provided with an eccentric, an eccentric-rod intermediate the said eccentric and the rock-arm for rocking the rock-shaft, and another eccentric-rod intermediate the said eccentric and the rigid arm on the sleeve for rocking the latter, substantially as and for the purpose herein described.

15 6. The combination, as hereinbefore set forth, with the drive-shaft 11, provided with

the eccentric 36, of the rock-shaft 7 and the loose sleeve 18 mounted thereon and provided with the packer 17, the arm 42, rigidly attached to the sleeve 18, and the eccentric-bar 45, connected to the eccentric 36 and pivoted to the arm 42, substantially as and for the purpose herein described.

7. The combination, as hereinbefore set forth, with the packer frame or arms, of one or more packer-blades 21, provided with teeth 22, formed each with a notch 46, substantially as and for the purpose herein described.

JOHN P. THOMPSON.
